UNITED STATES PATENT OFFICE.

GEORGE T. BOYLAN, OF HARTFORD, CONNECTICUT.

INCORRECT-POSITION INDICATOR.

1,275,522.

Specification of Letters Patent. Patented Aug. 13, 1918.

Application filed February 13, 1917. Serial No. 148,456.

To all whom it may concern:

Be it known that I, GEORGE T. BOYLAN, a subject of the King of Great Britain, residing at Hartford, in the county of Hartford 5 and State of Connecticut, have invented a new and Improved Incorrect-Position Indicator, of which the following is a specification.

My invention relates to the class of devices that are employed to denote when a person is assuming an incorrect position, and especially as regards the position necessary for correct breathing, and an object of my invention, among others, is to provide a device of this class that may be conveniently worn and that will be particularly sensitive in denoting any material departure or movement from a correct position of the person wearing the device.

20 One form of indicator embodying my invention and in the construction and use of which the objects herein set out, as well as others, may be attained, is illustrated in the accompanying drawings, in which—

25 Figure 1 is a perspective view of my improved indicator.

Fig. 2 is an edge view in lengthwise section through the case.

30 Fig. 3 is a view in lengthwise section through the case looking from the front.

In the accompanying drawings the numeral 5 indicates shoulder straps, made of any suitable flexible material and provided with any desired means, as buckles, for attaching the ends together, these straps being made to extend from the back of the wearer over the shoulders to the front, and of a length to support a girdle 6 constructed to extend around the body underneath the 35 arms, this girdle being provided with any suitable means, as a buckle, for securing it in place. A case 7 of any suitable form and material is secured to the girdle 6 and encloses the indicating mechanism.

40 A post 8 secured to the base plate 9 of the case has a gear 10 rotatably mounted thereon, this gear having a pinion 11 rigidly connected therewith, the teeth of which mesh with a rack lever 12 attached to the base by a pivot 46. A bar 13 is pivotally connected to the lever 12 and to a frame 14, the latter receiving one end of an actuating strap 15 extending through an opening in the wall of the case and attached at its outer 45 end to a buckle 16 or other means for securing one end of the girdle. The strap 15 passes

over an idle roll 17 rotatably mounted between ears 47 projecting from the base 9. Springs 18 hold the frame 14 at one limit of its zone of movement. 60

The gear 10 meshes with a pinion 19 rotatably mounted on a post 48 extending from the base 9, said pinion having a gear 20 rigidly connected therewith and meshing with an indicator gear 21, the latter having an 65 indicator hand 22 rigidly connected therewith and operating in connection with a graduated dial 23 to denote the degree of movement of the indicating hand.

The gear 20 carries a contact stud 24 positioned to strike either of the arms 25 of a forked contact 26. These arms are adjustable one with respect to another as by means of a screw 27 having a head with a beveled under surface to engage between the 75 arms 25 and force them apart against the pull of a spring 28.

The contact 26 is mounted on a base 29 located on a block 30 of insulating material, a conductor 31 extending from the base 29 80 to the base 32 of an audible signal, as a buzzer 33, said buzzer being connected by a conductor 34 with a spring conductor 35 supported on a post 36 composed of insulating material or separated from the base by 85 such material.

The conductor 35 is held, by its resilient action, in contact with one terminal 37 connected with one pole of a battery 38, the other pole of which is connected with a 90 terminal 39 that is in contact with a conducting post 40 that serves as a means of grounding the battery. From this construction it will be noted that the terminal 39 is electrically connected with the stud 24 on 95 the gear 20, this through the base 9 and post on which the gear 20 is mounted, and as soon as said stud 24 strikes either of the contact arms the electrical circuit is completed.

A spring clip 41 is secured to the base and 100 is formed to partially envelop the battery 38 and hold it in place. A cover 42 is hinged to the front wall of the case, as shown in Fig. 1 of the drawings, and a catch 43 of any suitable form and construction is provided to hold the cover in its closed position, in which position the battery will be retained with its terminals touching the conductors 37 and 40.

It has been found that the affliction of 110 stuttering or stammering is largely due to imperfect breathing and in order to breathe

correctly it is important that the body shall be erect and the shoulders thrown back, and it has been found that this erect position is of great importance in treating the affliction 5 of stammering or stuttering. My invention seeks to provide a device that shall give notice when the wearer has assumed an imperfect position and also to denote when the breathing is imperfect.

- 10 To secure these results my improved device is adjusted around the body just underneath the arms, the end of the strap 15 being drawn through the buckle to cause the device to fit quite close when the person is in 15 proper position as to the shoulders. The parts are so arranged that when the strap 15, which in fact forms a part of the girdle, is drawn to the proper extent the stud 24 will be located about midway between the 20 arms 25. As the person breathes, when this is thus adjusted, the stud 24 will oscillate between the arms without touching them and in order that this oscillation may be to a greater or lesser extent to accommodate different ranges of breathing in different persons, the adjusting screw 27 is provided so that the arms may be separated or brought closer together.
- Should the person wearing the device allow 30 his shoulders to move forward and the chest to be depressed, the strap 15 will be drawn inwardly by the springs 18 and through the connecting mechanism the rack bar 12 will operate the several pinions and 35 gears and the stud 24 will be moved into contact with one of the arms 25 whereupon the signal will be sounded and the person will be notified that he has assumed an incorrect position.
- 40 Likewise in breathing, should the inhalations and exhalations become irregular, that is too great or too little and not regular, the contact stud 24 will be thrown against one of the arms 25, depending upon whether the 45 inhalation or exhalation is in excess, and the alarm will be sounded and the person will thus be notified of an abnormal condition with respect to his body.

The visual signal including the hand 22 50 and dial 23 is operated through the gearing hereinbefore described and by means of this visual signal an attendant, having charge of the patient wearing the device, may observe the conditions as to breathing or abnormal 55 position of the shoulders without the patient being conscious of such observation.

A cut-out is provided to break the electrical circuit when the device is unattached to a person and the strain is, therefore, removed 60 from the strap 15 and the stud 24 is consequently in electrical contact with one of the arms 25. In the construction herein shown a cut-out slide 44 is mounted on the wall of the case in position for its beveled 65 end to engage the terminal 39 and force it

from electrical contact with the conductor 40. A knob 45 is provided wherewith to operate said slide and the knob and slide will be constructed to provide sufficient friction to hold the slide in any position to 70 which it may be moved.

In accordance with the provisions of the patent statutes I have described the principles of operation of my invention, together with the apparatus which I now consider to 75 represent the best embodiment thereof; but I desire to have it understood that the apparatus shown is only illustrative, and that the invention can be carried out by other means. 80

I claim:

1. An indicating device including a base, an indicator mounted on the base, a controlling member movably mounted on the base and normally disconnected from said indicator, means for connecting said controller and indicator, and a girdle comprising a part movably attached to the base and operatively connected with said controlling member to actuate it. 90

2. An indicating device including a base, an indicator mounted on the base, a controlling member movably mounted on the base to control operation of said indicator, means connected with the indicator and located for engagement by the controlling member in its movement in opposite directions, and a girdle comprising a part movably mounted on the base and operatively connected with said controlling member. 100

3. An indicating device including a base, an indicator mounted on the base, a forked member connected with the indicator to effect operation thereof, a controlling member mounted for movement in opposite directions between the arms of the forked member, and a girdle comprising a member movably mounted on the base and operatively connected with said controlling member to effect movement thereof. 105

4. An indicating device including a base, indicators of different character mounted on the base, actuating means for said indicators, and a girdle including a member movably attached to the base and mechanically connected with said indicators. 115

5. An indicating device including a case, a battery, conductors positioned in the case to be engaged by terminals of said battery, means for positioning the battery in the case for engagement of said terminals and conductors, an indicator located within the case and operatively connected with said conductors, an actuating device, and means for connecting said indicator with said actuating 120 device. 125

6. An indicating device including a case, means for attaching said device to the body of a person, an indicator mounted within the case, a battery, conductors located within the 130

case in position to receive contacts of said battery, means for positioning said battery in the case with its contacts in electrical connection with said conductors, a controlling member positioned to control the operation of said indicator by said battery, and means operatively connected with said controlling member and with said attaching means and actuated by means of the body of the person to which the device is attached.

7. An indicating device including a case, an indicator mounted within the case, a battery, conductors located within the case in position to receive contacts of said battery, means for positioning the battery within the case with its contacts in electrical connection with said conductors, a controlling member positioned to control the operation of said indicator, and a girdle for attaching the case to a person, said girdle including a part operatively connected with said controlling member to actuate it.

8. An indicating device including a case, means for attaching said device to the body of a person, indicators of different character located within the case, a battery, conductors located within the case to receive contacts of said battery, means for positioning the battery within the case with its contacts in electrical connection with said conductors, actuating means operatively connected with all of said indicators, and a member operatively connected with said actuating means and with said attaching means and adapted to be operated by means of the body of a person to which the device is attached.

9. An indicating device including a base, means for attaching said device to the body of a person, an indicator mounted on the base, actuating means movably mounted on the base and including a movably mounted frame operatively connected with said indicator, and a girdle having one end attached to said frame to move it by reason of the movements of the body of a person to whom the device is attached.

10. An indicating device including a base, a plural number of indicators mounted on the base, actuating means movably mounted on the base and operatively connected with each of said indicators, said actuating means including a movably mounted frame, and a girdle having one end attached to said frame to move it by reason of movements of the body of a person to whom the device is attached.

11. An indicating device including a base, means for attaching said device to the body of a person, actuating means movably mounted on the base and including a train of gears and an actuating member therefor, an indicator mounted upon the base and operatively connected with said train of gears, and means operatively connected with said attaching means to operate the train of gears

by reason of movement of a body of a person to whom the device is attached.

12. An indicating device including a base, actuating means movably mounted on the base, and including a movably mounted frame and a train of gears operatively connected with said frame, an indicator mounted on the base and operatively connected with the train of gears, and a girdle having one end attached to said frame to move it by reason of movement of the body of a person to whom the device is attached.

13. An indicating device including a base, means for attaching said device to the body of a person, a train of gears mounted on the base, means operatively connected with said attaching means to operate said gears by reason of movement of the body of a person to whom the device is attached, an indicator mounted on the base, a contact stud supported by one of the gears, and a contact arm mounted in the path of movement of said stud and operatively connected with said indicator.

14. An indicating device including a base, means for attaching said device to the body of a person, a train of gears mounted on the base, means operatively connected with said attaching means to operate said gears by reason of movement of the body of a person to whom the base is attached, an indicator mounted on the device, a contact stud carried by one of said gears, and a forked contact having arms located in the path of movement of said stud and operatively connected with said indicator.

15. In indicating device including a base, means for attaching said device to the body of a person, a train of gears mounted on the base, means operatively connected with said attaching means to operate said gears by reason of movement of the body of a person to whom the device is attached, an indicator mounted on the base and having an indicating hand operatively connected with said gears, a second indicator mounted on the base, a contact stud carried by one of said gears, and a controlling member operatively connected with the last mentioned indicator and having an arm located in the path of movement of said stud.

16. In indicating device including a base, an indicator mounted on the base, actuating mechanism mounted on the base and operatively connected with said indicator, said mechanism including a contact member, a source of electric energy located within the case to be controlled by said contact member, means operatively connected with said contact member and to attach the base to a person, and means for preventing electrical connection of said contact member with said source of electric energy.

17. In indicating device including a base, an indicator mounted on the base, actuating

mechanism mounted on the base and operatively connected with said indicator, said mechanism including a contact member, a source of electric energy located within the case and controlled by said contact member and including movable terminals, means for attaching the device to a person, said means being movably connected with said actuating mechanism, and means for moving one of said terminals to break the electrical circuit.

18. An indicating device including a base,

means for attaching the device to a person, an operating member movably mounted on the base and operatively connected with said attaching means, a contact device including two members movable one with respect to the other, a controlling member operatively connected with said operating member, means for changing the relative position of said controlling member and the members of said contact device, and an indicator operatively connected with said contact device.

GEORGE T. BOYLAN.
